UNITED STATES PATENT OFFICE.

ALEXANDER BALVANOVICH, OF BROOKLYN, NEW YORK.

SHOE-CLOSURE.

1,291,365.

Specification of Letters Patent.

Patented Jan. 14, 1919.

Application filed September 27, 1917. Serial No. 193,441.

To all whom it may concern:

Be it known that I, ALEXANDER BALVANOVICH, a subject of the Czar of Russia, resident of Brooklyn, county of Kings, and 5 State of New York, have invented certain new and useful Improvements in Shoe-Closures, of which the following is a specification.

This invention relates to improvements in 10 shoes, and particularly to types adapted to be closed at the rear or heel portion thereof.

The principal object of the invention is to provide means whereby the shoes can be closed in a secure and convenient manner, 15 thereby avoiding unsightly obstructions at the front or sides of the shoe.

A further object is to provide such means in forms which will prevent the entrance of 20 snow or water, and which present a neat and attractive appearance.

These and other like objects are attained by the novel construction and combination of 25 parts hereafter described and shown in the accompanying drawings, forming a material part of this disclosure, and in which—

Figure 1 is a similar horizontal sectional view showing the fastening means.

Fig. 2 is a perspective view showing a 30 fragment of the securing means, and

Fig. 3 is a similar perspective view showing a fragment of the securing means as employed on the other side of the shoe.

In Figs. 1 to 3 is shown a form of closing means, in which the sides of the shoes 20 and 35 22, have securely engaged at their edges, stemmed hooks 26 and 28, the same standing directly outward and adapted to pass through openings 27 and 29, formed through flaps 30 and 32, engaged respectively at the

rear of the vamps 20 and 22, the flaps extending outwardly so as to pass each other 40 when in an operative position, and held by the points of the hooks so as to form an impervious joint, reinforced by the strip or tongue element 33, on which are formed the slots through which the hooks pass prior to 45 entering the slots in the flaps, as can best be seen in Fig. 1.

From the foregoing, it will be seen that a neat and convenient manner of securing shoes has been disclosed and that the same 50 are tightly held in an engaged position when the foot is entered within the shoe.

Having thus described my invention what I claim as new and desire to secure by Letters Patent, is—

1. In a shoe closing device, the combination with the counter of a shoe, and vamp thereof, of hooks spacedly arranged on the opposed edges of said vamp, and flaps united to the exterior of said vamp, said flaps having openings receptive of said hooks and being adapted to lap one past the other.

2. In a shoe closing device, the combination with a relatively rigid counter and a vamp having spaced edges directly at the rear of the shoe, hooks united to the edges of said vamp, flaps secured to the exterior of said vamp, one upon either side of the mentioned edges and adapted to engage one with the other, said flaps having horizontal slots receptive of said hooks, and a flexible reinforcing tongue engaging with said hooks prior to the attachment of said flaps.

In testimony whereof I have affixed my signature.

ALEXANDER BALVANOVICH.
